HOLDER FOR PAPER CUPS

Walter E. Amberg, Beverly Shores, Ind., and Bernard F. Alm, Elgin, Ill., assignors, by mesne assignments, to Lily-Tulip Cup Corporation, New York, N. Y., a corporation of Delaware.

Application July 13, 1946, Serial No. 683,440

3 Claims. (Cl. 65—61)

1

This invention relates to cup holders for paper cups and more particularly to cup holders having means for automatically gripping the paper cup when it is received within the holder.

The principal object of this invention is to provide an improved gripping means in the cup holder for automatically gripping a paper cup when it is received within the holder. By reason of the improved gripping means, the cup holder may be placed over the top paper cup of an inverted stack of cups for positively gripping the top paper cup to pick it up from the inverted stack. The improved gripping means also serves to retain the paper cup in the holder in a positive and efficient manner.

In accordance with this invention the improved gripping means may comprise a resilient annular pickup member made from a resilient plastic material such as "Tygon" or rubber composition, or other suitable resilient material, and the resilient annular pickup member resembling a washer in appearance may be provided with slits terminating in holes, which together form a plurality of inwardly extending fingers. Upon reception of a conical paper cup in the pickup holder the fingers are displaced and the portion of the member immediately beyond the fingers or holes is distorted and stretched by the paper cup for automatically gripping the paper cup. The fingers and the portion immediately beyond the fingers form respectively primary and secondary grippers and the fingers prevent the distorted and stretch portion of the secondary gripper of the member from reversing its position and causing accidental release of the cup.

A further object of this invention is to provide the resilient annular pickup member or washer with a thickened edge to facilitate securing the resilient washer within the holder. The thickened edge, in accordance with one form of this invention, may be provided with a groove for receiving an internal flange in the holder for the purpose of securing the resilient washer in the holder. In accordance with another form of the invention, the thickened edge of the resilient washer is adapted to be received in an internal annular groove in the holder for securing purposes. In a further modification the thickened edge of the resilient washer may be adhesively secured within the holder.

Further objects of this invention reside in the details of construction of the various forms of pick-up holders.

Other objects and advantages will become apparent to those skilled in the art upon reference

2

to the accompanying specification, claims, and drawing, in which:

Fig. 1 is an elevational view showing a cup holder applied to an inverted stack of paper cups;

Fig. 2 is an enlarged sectional view through one form of the cup holder;

Fig. 3 is a sectional view similar to Fig. 2 but showing a paper cup received within the cup holder;

Fig. 4 is a plan view of the resilient annular pickup member or washer with the thickened edge utilized in Figs. 2 and 3;

Fig. 5 is an enlarged sectional view through a portion of the cup holder and through the resilient annular pickup member or washer between the slits;

Fig. 6 is a view similar to Fig. 5 but with the section being taken along the slits;

Fig. 7 is an enlarged partial sectional view of a modified form of cup holder and resilient annular pickup member or washer; and

Fig. 8 is a sectional view of still another form of cup holder and resilient annular pickup member or washer.

The cup holder is generally designated at 10 and is adapted to receive a paper cup, such as a conical paper cup 11, and as shown in Fig. 1 the paper cups may be included in an inverted stack 12.

In order to receive a paper cup in the cup holder from an inverted stack of cups all that is necessary is to place the cup holder over the top paper cup of the inverted stack and the gripping means in the cup holder will automatically grip the top cup of the inverted stack and retain the cup within the holder. In this way when the holder is removed from the stack, the top paper cup is removed therewith and is positively retained in the holder. This provides a simple means for inserting paper cups in cup holders.

The cup holder 10, as shown in Figs. 2 and 3, comprises a base portion 14 and a receptacle portion 15. The receptacle portion 15 is reduced in diameter at 16 to be telescopically received in the base portion 14. In this way the base portion 14 and receptacle portion 15 are secured together forming a throat therebetween and the securing may be done either by a tight fit, by welding as in the case of metal cup holders, or may be adhesively secured together as in the case of plastic holders. The receptacle portion 15 is also provided with an inturned flange 17 for securing in

the throat of the holder a resilient annular pickup member or washer 20.

The resilient annular pickup member 20 resembles a washer in appearance and is preferably made of a suitable resilient plastic material such as "Tygon," rubber composition or other suitable resilient material and it forms the automatic gripping means for retaining a paper cup within the holder.

The resilient annular pickup member or washer 20 is provided with an internal opening 21 and a plurality of slits 22 leading therefrom. The slits terminate in holes 23 in order to provide a plurality of resilient grippers for the paper cup. The edge of the resilient annular pickup member or washer 20 is thickened as at 24 to fit against the side walls of the cup holder 10 and the thickened portion is provided with a circumferential groove 25 for receiving the inturned flange 17 of the holder 10. The resilient washer 20 is inserted in the cup holder 10 with the thickened edge 24 engaging the side walls of the holder 10 and with the circumferential groove 25 receiving the inturned flange 17 whereby the resilient annular pickup member or washer 20 is firmly secured in place within the holder 10 and it assumes the position shown in Fig. 2.

When a paper cup is received in the receptacle portion 15, the resilient washer 20 is displaced by the paper cup and is internally forced downwardly, as shown in Figs. 3, 5 and 6. The fingers or portions of the resilient washer between the slits 22, grip the side walls of the paper cup and therefore form what may be termed primary grippers. The gripping action of the primary grippers depends primarily upon the resiliency of the displaced fingers between the slits 22. The portion of the resilient washer immediately beyond the fingers and holes 23 is distorted by the reception of the paper cup and the tendency is to stretch the resilient washer at that portion. The portion of the resilient washer immediately beyond the holes 23 in resisting this stretching tendency, therefore, form what may be termed a secondary gripper for the paper cup. The fingers prevent the distorted and stretched portion of the member from reversing its position and accidental release of the cup. The primary gripping action is more clearly illustrated in Fig. 6, while the joint primary and secondary gripping actions are more clearly illustrated in Fig. 5. Because of these gripping actions the paper cup 11 is positively retained within the holder 10 until such time as the paper cup is forcefully extracted therefrom.

While the resilient annular pickup member or washer 20 having the circumferential groove 25 in the thickened edge thereof is particularly adaptable for use with a metal cup holder formed of two pieces with one of the pieces provided with an inturned flange as shown in Figs. 2-6, it may be utilized with other types of cups such, for example, as plastic cups provided with a molded internal flange.

Fig. 7 shows a modified arrangement for securing a resilient annular pickup member or washer in a one-piece cup formed of plastic or cast from metal. In Fig. 7 the cup holder is generally shown at 10A and includes a base portion 30 and a receptacle portion 31 merging at 32 in a throat therebetween. The resilient annular pickup member or washer is designated at 33 and the central opening, the slits and holes, may be the same as those illustrated in Fig. 4 and, therefore, like reference characters have been utilized. In

Fig. 7, however, the thickened edge 34 of the resilient washer 33 is of regular configuration and is received in an internal groove 35 formed in the holder 10A. The resilient washer 33 may be inserted in the holder 10A by deforming it and then allowing the thickened edge 34 thereof to expand into the internal groove 35, whereupon the resilient washer is firmly held in place. The gripping operation of the washer 33 of Fig. 7 is the same as that of the washer 20 previously explained and, therefore, a further description at this point is not considered necessary.

In Fig. 8 the resilient annular pickup member or washer is particularly adaptable for use in a one-piece cup holder which may be formed of metal by a spinning operation. Here the cup holder is generally designated at 10B and includes an integral base portion 40 and a receptacle portion 41 merging together at 42 in a throat therebetween. The resilient annular pickup member or washer is designated at 43 and includes the same central opening slits and holes as shown in Fig. 4. Here, however, the thickened edge 44 of the resilient washer 43 is of such configuration as to fit within the holder adjacent the point of merging of the base portion and the receptacle portion, and the thickened edge 44 is adhesively secured within the throat of the holder 10B by a suitable cement or glue. A suitable tool may be utilized for accurately locating the resilient washer 43 in place in the holder 10B. The gripping action of the arrangement shown in Fig. 8 is substantially the same as those previously described, and, therefore, a further description at this point is not considered necessary.

While for purposes of illustration several forms of this invention have been disclosed, other forms thereof may become apparent to those skilled in the art upon reference to this disclosure and, therefore, this invention is to be limited only by the scope of the appended claims and prior art.

We claim as our invention:

1. A pickup holder for paper cups comprising, a base portion, a receptacle portion carried by the base portion, an internal flange in the holder, a resilient annular pickup member having a thickened edge provided with a groove for receiving the flange to secure the resilient annular pickup member in the holder, the inner portions of said resilient annular pickup member to be distorted by a paper cup when received in the receptacle portion for automatically gripping the same.

2. A pickup holder for paper cups comprising, a base portion, a receptacle portion, means for securing together the two portions, one of the portions being provided with an internal flange, a resilient annular pickup member having a thickened edge provided with a groove for receiving the flange to secure the resilient annular pickup member in the holder, the inner portions of said resilient annular pickup member to be distorted by a paper cup when received in the receptacle portion for automatically gripping the same.

3. A substantially hollow pickup holder for preformed conical paper cups comprising a base portion, a substantially conical cup receptacle portion joining the base portion, the juncture forming a throat between the base and receptacle portions, said receptacle portion receiving and supporting a preformed conical paper cup with the apical end of the paper cup extending into said throat, an internal flange in said throat,

a resilient annular pickup member located in said throat and having a thickened edge provided with a groove for receiving the flange to secure the resilient annular pickup member in the throat, the inner portion of said resilient annular pickup member to be distorted by paper cup when received in the receptacle portion for automatically gripping the same.
